US00D989012S

(12) **United States Design Patent** (10) **Patent No.:** **US D989,012 S**
(45) **Date of Patent:** **** Jun. 13, 2023**

(54) **ELASTIC MEMBRANE**

(71) Applicant: **EBARA CORPORATION**, Tokyo (JP)

(72) Inventors: **Kenichi Akazawa**, Tokyo (JP); **Osamu Nabeya**, Tokyo (JP); **Shingo Togashi**, Tokyo (JP); **Satoru Yamaki**, Tokyo (JP); **Tomoko Owada**, Tokyo (JP); **Cheng Cheng**, Tokyo (JP); **Yuichi Kato**, Tokyo (JP)

(73) Assignee: **EBARA CORPORATION**, Tokyo (JP)

(**) Term: **15 Years**

(21) Appl. No.: **29/774,336**

(22) Filed: **Mar. 16, 2021**

(30) **Foreign Application Priority Data**

Sep. 17, 2020 (JP) ..... 2020-019863 D
Sep. 17, 2020 (JP) ..... 2020-019864 D

(57) **CLAIM**

The ornamental design for an elastic membrane, as shown and described.

DESCRIPTION

FIG. 1 is a top perspective view of an elastic membrane showing our new design;

FIG. 2 is a bottom perspective view thereof;

FIG. 3 is a top plan view thereof;

FIG. 4 is a bottom plan view thereof;

FIG. 5 is a front view thereof, a rear view being identical thereto;

FIG. 6 is a right-side view thereof, a left-side view being identical thereto;

FIG. 7 is a cross sectional view taken along section line 7-7 in FIG. 3; and,

FIG. 8 is an enlarged portion view taken along line 8-8 of FIG. 7.

The broken lines in the drawings depict portions of the elastic membrane that form no part of the claimed design.

1 Claim, 8 Drawing Sheets
